CLAIM

The ornamental design for a boat monitor for detecting emergencies and for sending signals to remote locations, as shown and described.

DESCRIPTION

FIG. 1 is a front, top and side perspective view of the boat monitor for detecting emergencies and for sending signals to remote locations embodying the design of the present invention;

FIG. 2 is a side elevational view thereof;

FIG. 3 is a side elevational view thereof;

FIG. 4 is a rear end elevational view thereof;

FIG. 5 is a front end elevational view thereof;

FIG. 6 is a top plan view thereof; and,

FIG. 7 is a bottom plan view thereof.

FIG.1

FIG. 2

FIG. 3

FIG. 4

FIG. 5

FIG. 6
